(57) **CLAIM**

The ornamental design for a bra strap securing device, as shown and described.

DESCRIPTION

FIG. 1 is a top plan view of the bra strap securing device of the present invention;

FIG. 2 is a side elevation view of the bra strap securing device of FIG. 1; and,

FIG. 3 is a bottom plan view of the bra strap securing device of FIG. 1.

The left and right sides of the design of the present invention are identical/symmetrical.
